UNITED STATES PATENT OFFICE

154,551

DESIGN FOR A HAMBURGER PATTY FORMING DEVICE

Homer W. Lang, Alameda, Calif.

Application August 26, 1947, Serial No. 141,073

Term of patent 3½ years

(Cl. D44—1)

To all whom it may concern:

Be it known that I, Homer W. Lang, a citizen of the United States of America, residing at 1707 Union Street, Alameda, California, have invented a certain new, original, and ornamental Design for a Hamburger Patty Forming Device, of which the following is a specification, reference being had to the accompanying drawing, forming a part thereof.

Fig. 1 is a view in perspective of a hamburger patty forming device embodying my new design;
Fig. 2 is another view in perspective;
Fig. 3 is a top plan view;
Fig. 4 is a view in section taken along lines 4—4 of Fig. 3; and
Fig. 5 is a view in side elevation thereof.

I claim:

The ornamental design for a hamburger patty forming device, substantially as shown.

HOMER W. LANG.
